UNITED STATES PATENT OFFICE.

WILLIAM P. QUENTELL, OF STAMFORD, CONNECTICUT, ASSIGNOR, BY MESNE ASSIGNMENTS, TO A. B. DICK COMPANY, OF CHICAGO, ILLINOIS, A CORPORATION OF ILLINOIS.

CALCULATING-MACHINE.

1,007,487. Specification of Letters Patent. Patented Oct. 31, 1911.

Application filed April 13, 1909. Serial No. 489,669.

To all whom it may concern:

Be it known that I, WILLIAM P. QUENTELL, a citizen of the United States, residing at Stamford, in the county of Fairfield and State of Connecticut, have invented certain new and useful Improvements in Calculating-Machines, of which the following is a specification.

My invention relates to calculating machines and its objects are to provide improved means for effecting the carrying of the numerals from one denomination to the next higher denomination, to provide means of a simple construction for preventing an undue movement of the gear mechanism of the number wheels, to provide a numeral wheel operating mechanism so constructed and associated with an operating lever that the entire operation may be effected by the manual pressure on the lever in one direction, relieving the return spring for the lever of any positive work, and to generally improve and simplify the construction of a machine of this class.

With these objects in view, my invention is embodied in preferable form, in the device hereinafter described and illustrated in the accompanying drawings.

In these drawings, Figure 1 is a plan view of a calculating machine containing my improvements, showing part of the casing removed, and also showing the machine partly broken, away, three rows of keys only, with two rows of buttons being shown; Fig. 2 is a vertical longitudinal section; Fig. 3 is an enlarged detail in elevation of the numeral wheel driving gear and the means for operating the same; Fig. 4 is a similar view, showing the pawl operated; Fig. 5 is a similar view showing in dotted lines, the parts in carrying position; Fig. 6, a detail elevation of driving arm, from opposite side to that shown in Figs. 3, 4 and 5; Fig. 7, a detail edge view of driving arm; Figs. 8 and 9, details of bell crank of carrying mechanism; Fig. 10, an enlarged detail in side elevation of printing mechanism operating means; Fig. 11, a detail of one side of a number wheel; Fig. 12, a detail of number wheel from opposite side; Fig. 13, an enlarged detail in side elevation of bail and operating cam for actuating the detents and bell crank latches; Fig. 14, a partial detail plan of the number wheel shaft; Fig. 15, a detail en-

larged plan of printing mechanism; Fig. 16, a detail elevation of repeating mechanism; Fig. 17, a detail perspective of pawl-setting slide-bar and a key; Fig. 18, a partial vertical section the reverse of the view of Fig. 3, but showing the pawl-carrying arm moved away from the driving arm; Fig. 19, a bottom view of two of the driving arms and pawl-carrying arms and their operating mechanism, and Fig. 20 is a detail perspective view of a driving arm and a pawl-carrying arm spaced apart on a portion of the main shaft.

Referring to the drawings 1 is the frame of the machine and 2 are keys which bear the usual series of numbers for calculating purposes, each key having a large and a small numeral in order that addition, subtraction and division may be employed, in the ordinary way. The keys are arranged in longitudinal columns and transverse rows of digits with such digits in each longitudinal column running from "1" to "9" of the major figures and from "8" to "0" of the minor figures. The stems 3 of the keys of each longitudinal row, are mounted so as to slide vertically on fixed longitudinal bars 4 by means of slots 5 in the key stems and pins 6 engaging such slots and extending from the bars. Individual springs 7 connected to the stems and pins serve to hold the keys normally in raised position. The stem has a vertical extension or arm 8 and is turned at right angles at its lower end to provide a heel 9, which is adapted to operate a sliding and oscillating angled bar 10 connected to 80 and adapted to operate the number wheel setting mechanism. (See Figs. 2 and 17). The number registering wheels (see Figs. 2, 16 and 17) are denoted by the reference character 11. The slide bar 10 is provided with two faces 12 and 13, and said slide bar is held normally in such position that the face 12 is tilted slightly upward from a horizontal position. A spring 14 connected to the slide bar 10 serves to normally hold 100 the said slide bar in upwardly tilted position and with a notch 15, of said bar, in engagement with a detent 16 in the bar 4, whereby the bar 10 is held projected toward the number wheels.

When a key is depressed the stem strikes the face 12 turning the slide bar, causing it to swivel and releasing it from its detent,

whereupon the bar is drawn toward the front end of the machine by a spring 17, connected at one end to the frame of the machine and at the other end to a link 18, 5 having a lug 19 loosely engaging a slot in the bar 10 and connected at the other end to the wheel setting mechanism. As the bar is retracted, a stop-tooth 20 in the bar will strike against the vertical arm 8 and stop the bar. 10 A series of such stop-teeth are provided, one for each key and they are so positioned relative to the keys, that the bar will move varying graduated distances according to which key in one of the longitudinal digit 15 series is depressed. Each end of the slide bar 10 has a reduced swiveling and supporting extension 21 extending through a hole in a fixed plate 22, whereby the slide bar is effectively supported at both ends and 20 guided in a straight path. To the rear end of link 18 is pivotally connected a pawl-carrying arm 23 which is loosely mounted by means of a sleeve on a main shaft 24, extending across the machine and journaled in 25 the side frames thereof. (See Figs. 2, 3 and 4). Pivoted on this arm is a pawl 25 adapted to engage a gear wheel 26 also loosely mounted on the shaft 24. The teeth of this gear wheel may either be of ordinary ratchet 30 form or preferably may be ordinary curved, spur gear teeth, with slight bevels on the rear side at the end to permit the pawl to move toward the front of the machine over them without engaging therewith. A spring 35 27 serves to normally hold the pawl against the gear teeth, such spring being connected to a pin 28 extending from the pawl through an enlarged hole 29 in the pawl-carrying arm. The gear wheel meshes with a pinion 40 30 carried by a sleeve 31 on which is also fixed the number wheel 11, which bears the numerals from "0" to "9", corresponding to and positioned relatively to the digits in the longitudinal row of keys in line with the 45 wheel.

The pawl 25 has a shoulder 32 against which is adapted to bear a pawl lock member 33 consisting of a curved lug extending from the edge of a driving arm 34. (See Figs. 50 4, 5 and 6). The pawl lock member need not bear positively upon the pawl, as a sufficiently close proximity to prevent the pawl escaping from the gear teeth will be sufficient. This driving arm 34 is loosely mounted on the main shaft 24. There is one driving arm for each number wheel and pawl and all the driving arms are connected and operated by a common bail 35 engaging channels in the driving arms and fixedly 55 connected to the rotatable main shaft by means of arms 36. These driving arms when oscillated toward the back of the machine by the main shaft are adapted to pick up and carry with them the pawl-carrying 60 arms and thus actuate the pawl so as to

carry back the number wheel a distance corresponding to the number of teeth of the pinion and gear over which the pawl has been carried by the key-actuated slide bar.

On one end of the main shaft outside the 70 frame is an operating lever 37 provided with a handle and pressed against by a return spring 38, which serves to return the lever to its normal, upright position after it has been operated by hand. By pressing the 75 lever downward, the driving arms, pawls and number wheels are actuated to register by these wheels, the numbers on the keys previously depressed. To this end, the pawl-carrying arm 23 has a contact member 80 consisting of a lug 39 extending from the arm at right angles thereto, into the path of a rocker member 40, pivoted on the driving arm and having a shoulder 41 against which bears the lug 42 of a trigger 43 which is pivoted on the driving arm and has a pointed or beveled end at 44 (see Figs. 6, 7, 5, 4 and 3). The rocker has a tooth 45, extending through an elongated arc-shaped slot 46 in the driving arm whereby the rocker is permitted a limited range of movement with 90 respect to the driving arm. A coiled spring 47 joins the trigger and an arm of the rocker and normally holds these parts in engagement, keeping the trigger down against the shoulder of the contact arm of the rocker and the shoulder behind the lug of the trigger.

In registering any amounts below and including 9, the proper key having been depressed and the pawl of the corresponding wheel thereby carried to the front of the machine, the proper number of teeth as determined by the particular key-stop on the slide bar, the handle-lever is depressed until 100 it comes in contact with a stop-pin 48, thereby rotating the main shaft 24 and by means of the bail 35-36, carrying toward the back of the machine all the driving arms 34 and the driving arm corresponding to the retracted pawl or pawls 25 will pick up the pawl carrying arms 23, by striking against the projecting contact lugs 39 and impel such arms so as to turn the corresponding gears 26 and pinions 30 and number wheels 115 11. To prevent the momentum imparted to the pawl carrying arm by the driving arm from carrying the former too far and thus turning another tooth of the gear and pinion, stop means for each pawl device is provided, consisting of a lug 49 and a circular abutment collar 49' fixed on a bell crank member 50, which is mounted so as to oscillate on a fixed shaft 51, a bell crank member being provided for each pawl device. The 120 end 23' of the pawl carrying arm is adapted to be limited in its movement against overthrow by the lug 49 in registering numbers under and up to "9" (see Figs. 4 and 19) but does not abut positively against the lug, 130

being separated therefrom by a slight space when the arm is in the thrown position, so as to avoid friction when the lug is moved away and the pawl-carrying arm is thrown a tooth further in the operation of carrying the addition from "9" to "10" from the wheel of the next lower column, as will be described. The lug 49 is normally in the path of the end 23' of the pawl carrier 23, but is adapted to be moved out of said path when the detent bell-crank member 50 is rocked by the next lower number wheel, when from such wheel the addition is to be carried over to the wheel of the higher decimal place. The trigger 43 and rocker 40 move together and are not actuated unless the addition is to be carried over from the lower wheel.

The carrying mechanism will now be described. Projecting forward from the upper part of the bell crank is an arm 52, with which is adapted to contact a rocker 53 on the side of the adjoining number wheel so that when the latter wheel has made a complete revolution and the "10" is to be carried to the next wheel the arm 52 will be tripped which will momentarily rock the bell-crank and carry the stop lug 49 out of the path of the point of the pawl-carrying arm of the wheel of the higher series, (see Figs. 5 and 19) whereupon the pawl-carrying arm of that higher series will be permitted to move forward far enough to carry the pawl one tooth on the gear and thus turn the higher number wheel a space and carry over the addition from the lower wheel. The rocker 53 is connected to a spring 135, which holds it normally in inoperative position against a stop-pin 136. See Fig. 12. A cam 137, either offset or formed by a slot, is provided on the partition plate 138, separating two adjacent number wheels and a pin 139 on the tail of the rocker 53 is adapted to bear against this cam as the wheel approaches the "9" position so that when the wheel reaches "9" the rocker will be tilted out sufficiently to project over the bell-crank arm 52. Then when the wheel goes from "9" to "10," the rocker remaining in its tilted position until it reaches the end of the cam, is released when it moves off the cam and its spring snaps it back to normal position and in so moving it hits the bell crank trip 52 and sets the bell crank corresponding to the next higher wheel for the "10" carrying position. The objects of this arrangement are to avoid the objections to a fixed projection on the wheel which are that owing to the liability of wear and consequent loose play of the parts there is danger that the projection, if positioned exactly at the point of coincidence of the trip to carry over during a short or average movement, as in moving from "8" to "10," will when being

carried to the "9" position be thrown over far enough to improperly set the crank to "10," to avoid which the projection must be set "late" on the wheel which involves the objection of a possible failure to operate the trip on a short movement of the wheel. The carrying movement is then effected by the point of the trigger 43 of the driving arm 34 of the higher wheel striking against the edge of a trip arm 54 on the bell-crank, which arm has been carried by the tilting of the bell-crank into the path of the trigger, thus releasing the rocker 40. See Figs. 5 and 19. It will be seen that the arm 52 of the bell-crank is actuated by one number wheel and the trip arm 54, trips the trigger corresponding to the actuating parts of the wheel of the next higher decimal place. A spring pressed rocking lever 55 mounted on a shaft 56 projects into the path of the tooth 45 of the rocker 40 and is pressed by said tooth at each actuating movement of the driving arm and upon the release of the rocker 40 from the trigger this lever 55 throws the rocker against the pawl-carrying arm and the pawl thus impelled turns the gear a tooth and the number wheel to the next higher number. As the bell-crank is shifted to this carrying position, a hook 57 thereon, engages and is held by a spring-pressed latch 58, mounted freely on a shaft 59, and having a tail piece 60 so as to hold the bell crank in proper position during the carrying operation.

A bail 61 extends across and under the tail pieces and is pivoted on the shaft 59 and has an arm 62 pivotally joined to a link 63. The link 63 has a pin which engages a cam slot 64 in a plate 65 carried by the main shaft and rocked thereby, by which connection the bail is adapted to release the latch 58 from the bell-crank hook. See Figs. 13 and 5. To the other end of the link 63 is pivoted an arm 66 of a rocking bail 67 contacting with spring pressed detents 68, adapted to be carried by their springs into engagement with the gears upon the rocking in one direction of the bail through the main shaft and cam slot 64, so as to thereby hold the gears from undue forward or registering movement, liable to be caused by the possible rebounding of the slide bar as it strikes the key stem in its retracting movement. The detents are withdrawn from the gears by contact of the bail immediately upon the initial movement of the operating handle for the purpose of permitting the proper registering operation of the gears and wheels.

Mounted on the upper part of the machine on a shaft 69 are spring-pressed detents 70 also adapted to engage the gears and to prevent backward rotation thereof, particularly when the driving pawls are ratcheting into place with the slide bar.

The bail 61 for the latches 58 and the bail 67 for the forward retaining detents 68 are linked together as shown and described, so that as one bail acts against the springs of its members, either latches or detents, the other bail moves away from the springs of its members and thus by having the springs of the two groups of members of substantially equal tension, with the tension of the one set opposed to that of the other, the operator in moving the handle is not obliged to exert extra power to overcome the force of either set of springs.

Means are provided (see Figs. 1 and 16) to enable the amount indicated by a depressed key or keys to be repeated in registering and such means comprise a small lever 76, mounted on a rocking shaft 77 which is provided with projecting pieces 78, adapted to strike against the transverse arm 79 of a sliding frame having longitudinal bars 80, which extend adjacent to and are guided by the bars on which the key-stems are mounted. These bars 80 have struck-out ears 81, one for each key, extending through the slots 82 in the key-stem supporting bars, and adapted when the lever 72 is pulled backward, to be carried by the sliding bars 80 over the projections 83 of any keys, that may be depressed, thereby holding the key down and preventing the pawl arm actuating slide bars from engaging their detents 16 so that the amounts indicated by the keys thus held down may be repeated by operating the main operating lever as many times as desired. Multiplication may be thus effected.

Extending upward through the frame at the rear of the machine are a series of error keys 84 pivoted to levers 85 mounted loosely on the main shaft and provided with arms 86. When a wrong key has been depressed and it is desired to correct the error before registering, the error key is depressed and therefore the arm 86 is lifted against the driving pawl so as to remove the same from engagement with the gear and carry the pawl backward to original position, which action at the same time releases the key from the slide bar and restores the slide bar to normal position.

To enable the number wheels to be re-set to "0," the number wheel shaft is slidably mounted in the frame so that it may be slipped sidewise until spring pressed pawls 87 carried on the hubs 88 of the wheels and projecting into the interior of the hubs, drop into grooves 89 in the shaft so that the wheels are then locked to the shaft and are forced to rotate with it. The grooves 84 are made slanting at each end in order that the pawls may readily slip into and out of the same. The wheels normally bear on the plain peripheral portions between the grooves. The shaft is normally locked from

rotation by the pin 90 at the right side of the machine which pin engages a hole 91 in a disk 92 at the end of the shaft. On the left hand end of the shaft is a small knob or disk 93 whereby the shaft may be pushed sidewise to cause the engagement of grooves and pawls as described. A spring 94 bearing against the frame and a collar 95 on the shaft serve to keep the shaft normally in position with its smooth peripheral portions receiving the number wheels. To effect the re-setting movement a pinion 96 is fixed on the number wheel shaft at the left end thereof and adapted to engage this pinion but normally out of engagement therewith is a gear segment 97 carried by the main shaft. The pinion is brought into engagement with the segment by the sliding movement of the number wheel shaft. The main shaft being then actuated by the handle will turn the segment pinion and wheel shaft, until the hole in the disk at the right end snaps over the pin on the frame, which happens when the operating lever has completed its forward stroke and turned the wheel shaft completely around, so as to bring all the wheels to "0."

In connection with the registering mechanism above described, I employ a recording mechanism which is preferably of the following construction. Pivoted at one end to each pawl carrying arm is a long link 98, the other end of which is intermediately pivoted to a printing wheel driving gear 99, which meshes with a pinion 100 carried by the hub of a printing wheel 101 which bears raised numeral type cut in the periphery of the wheel. A series of such wheels and operating mechanisms is provided, one set for each number wheel. A detent bail 102 extends across the wheels and is adapted to be moved into locking engagement therewith upon the printing movement of the platen. It will be seen that as the pawl carrier is moved the required number of teeth corresponding with the depressed key, it imparts the same movement through the link 98 to the type wheel and thus brings the required number to printing position. Mounted beyond the printing wheel is a tilting carriage 103, upon an axis rod 104, having side pieces 105 held together by bolts 106 and 107. In this carriage is mounted on spring arms 108 a platen 109. The object of the resilience of the platen arms is to permit a slight yielding in case the carriage is not released exactly at the moment that the platen strikes the printing wheel. The carriage is shown at normal position with the bolt or bar 107 resting against a stud 110 rising from the base of the machine.

The carriage is tilted forward so as to rock the platen against the printing wheel by means of a link 111 pivoted at one end to a stud projecting out from the right side

of the carriage. The link extends along the right hand side of the machine and at the other end has a cam face 113, adapted to ride on a pin 114, projecting from the side 5 of the machine. A projection 115 projects downward from the link and is adapted to be struck so as to carry forward the link by a cam 116 mounted on the main shaft 24. As the main shaft is operated by the depression 10 of the lever, the link will be carried forward by the contact of the cam 116 against projection 115, thus pulling forward the carriage and impelling the platen against the type wheels. As the platen strikes the type 15 wheels, a horn 117 carried by the carriage strikes against the detent bail 102 impelling the latter into engagement with the teeth of the type wheels and firmly locking them during the printing impression. In its continued forward movement the link will be 20 raised by the contact of its cam face 113 on the pin 114, so as to carry the projection 115, above the actuating cam 116, thus permitting the platen and carriage to return to normal 25 position. This return of the carriage is quickened in order to insure the withdrawal of the platen from the printing wheel before the main shaft picks up the adding mechanism, by means of a lever 118 mounted on 30 the pivot 119 at the side of the machine, and having its lower arm in the path of a pin 120 projecting from the cam 116. The upper arm of the lever extends into line with a pin 121 on the link. As the operating 35 lever is continued in its forward and downward movement, the pin 120 will strike against the lower arm of the lever 118, moving the upper arm of the lever against the pin 121, thus throwing the link back 40 sharply. A spring 122 near the other end of the link tends to keep the link held downward. On the return movement of the operating lever projection 115 rides over the cam 116 and the link snaps back into position. 45

Mounted on an upright 123 is a pawl 124 having a tooth 125, which engages a ratchet 126, on a shaft 127, carrying a paper pressing roll 128. Between the roll and a co- 50 operating roll 129, a strip of paper is adapted to be fed. As the carriage swings forward, the ratchet 126 causes the pressure roll 128 to rotate so as to feed the strip of paper. A stud 130 is mounted in the carriage and is adapted to coöperate with the pawl 124 to lift the same out of engagement with the ratchet as the carriage moves forward, so as to release the ratchet wheel and stop the feed of paper thereby determining 55 the amount of paper fed at each movement and also stopping the feed of paper at the moment of printing. A paper carrying roller 131 is mounted on the base of the machine at the rear and the paper is led therewith from up between the paper feeding rolls and

across the platen. Any suitable inking mechanism may be employed.

The general operation of the machine is as follows: When a key is depressed it turns the corresponding slide bar 10 causing the 70 same to swivel and releasing said bar from its locking detent and permitting its spring to retract it toward the front of the machine until the lug on the slide bar corresponding to the key strikes against the extension 75 of the key thus determining the extent of movement of the slide bar. By this action the pawl-carrying arm 23 is retracted by the link 18 and the pawl 25 thereby set at the proper tooth on the gear 26 to rotate the number wheel to the proper numeral. At 80 the same time the pawl-carrying arm will have drawn back the link 98 connected to the segmental gear 99, so as to set the corresponding type wheel at the proper numeral 85 for printing. The operating lever 37 is then depressed by hand, so as to turn the main shaft 24. This movement of the main shaft first moves the cam 116 into engagement with the projection 115 of the link 90 111 so as to start the platen carriage on its forward printing movement. The actuation of the carriage and the printing operation is completed before the lever moves far enough to effect the adding operation. At 95 the beginning of its movement also the main shaft through its cam-slot and bail 67 frees the forward locking detents 68 from the gears, and carries the pawl-lock 33 of the driving arm 34 into locking position. The 100 further movement of the shaft carries the driving arm against the pawl-carrying arm so as to carry the pawl back and operate the gear pinion and number wheel. If the stop-lug 49 of the bell crank of any wheel has 105 been moved up by the contact of the lip 53 of the adjoining wheel of the next lower column, then the latch 58 catches the hook of the bell crank 50 so as to hold the bell crank in carrying position before the wheel 110 that actuates it has finished its movement, and the trigger 43 being tripped, the rocker 40 on the driving arm will be impelled by 115 the lever 55 against the pawl-carrying arm and the pawl carried one tooth so as to effect the carrying operation. As the pawl-carrying arm is moved forward it carries back to its normal position in engagement with its detent, the key-actuating slide bar. The printing has also been effected and the 120 platen returned before the new addition takes place.

To print the numerals closely together the type wheels are positioned closely, and to obtain a straight pull between the number wheel actuating means and the type wheel gear the link 98 lies in the same vertical plane throughout its length. To accommodate this arrangement to the compactly arranged type wheels, each link is pivoted to 130

an arm 132 pivoted on the shaft carrying the type wheel gear segments. This arm is connected to a bar 133 at right angles to the arm and extending from the end of an arc-shaped arm 134, of the gear segment. The arc-shaped arms of the gears in one or more series are successively placed in advance of one another, so that as the gears are operated the bars 133 may pass one another freely. Thus, the arm 132 farthest to the right of the machine and corresponding to the right hand column of number wheels is connected to the bar farthest toward the rear from the axis of the gear. A series of five of the stepped arm gears may be arranged on the right hand side and a similar series on the left hand side.

It will be seen that all these operations are effected by the movement of the operating lever in one direction, by the force exerted by the hand of the operator.

It is necessary to reset the latches after each operation of the operating lever and before such lever is actuated again, otherwise with the latch holding the bell cranks in carrying position, the carrying would be continued indefinitely. Hence the bail 61 is so actuated by the cam slot as the operating lever is finishing its return stroke as to lift the latches and then the springs on the bell crank return the latter to their normal positions. At the same time the forward locking detent or pawls are returned to locking position.

Having thus described my invention, what I claim is:

1. In a calculating machine, in combination with a main shaft, a series of number wheels, means intermediate the main shaft and number wheels for turning the latter, a rocker member carried by the intermediate means, a spring for rocking said rocker member, means for holding the rocker member from being moved by the spring and means to release said holding means to permit the spring to move the rocker member to cause the wheel operating means to impart an extra movement to the number wheels to carry the numerals from one series to the next higher series.

2. In a calculating machine, in combination with a series of number wheels, a main shaft, a wheel turning member, a pivoted rocker member, a movable carrier for said rocker member, a spring for operating said rocker member to cause the wheel turning member to turn the wheel an extra space to carry the tens from one wheel to the wheel of the next higher series.

3. In a calculating machine, in combination with a main shaft, a series of number wheels, an oscillatory driving arm, a gear mechanism for each number wheel, an actuating pawl for said gear mechanism, a rocker member carried by said driving arm and

means whereby the rocker arm moves with the driving arm to impel the pawl, a spring for moving the rocker relative to the driving arm to impel the pawl an extra tooth, means for holding said rocker against said relative movement and means for releasing said holding means.

4. In a calculating machine, in combination with a series of number wheels, a main shaft, a driving arm mounted on the main shaft, wheel turning mechanism, a rocker member carried by the driving arm and adapted to contact with the wheel turning mechanism, a spring pressed lever against which one end of the rocker member bears at each actuation of the driving arm; means to hold said rocker from movement by said lever and means to release said holding means.

5. In a calculating machine, in combination with a series of number wheels, a main shaft, an oscillatory driving arm mounted on the main shaft, a gear wheel for each number wheel, a gear turning member, a rocker member mounted on the driving arm and adapted to bear against the gear turning member to actuate the same, said rocker having a shoulder at one end, means to engage the shoulder to hold the rocker fixed relative to the driving arm, a tooth at the other end of the shoulder, a spring exerting pressure against said tooth at each movement of the driving arm and means to trip the shoulder engaging means.

6. In a calculating machine, in combination with a series of number wheels, a main shaft, a driving arm, a pawl-carrying arm and pawl carried thereby, a number wheel driving gear engaged by said pawl, a rocker member carried by said driving arm and having a contact part adapted to strike against the pawl, said driving arm having a slot and said rocker having a tooth projecting through said slot, a spring pressed lever in the path of movement of said tooth, a trigger mounted on the driving arm for holding the rocker against movement by said lever and means operated by the number wheels for tripping said trigger to release the rocker and permit the lever to move the same an extra movement.

7. In a calculating machine, in combination with a main shaft, a series of number wheels, a driving arm actuated from the main shaft, a pawl, a pawl-carrying arm, a number wheel driving gear, and a carrying mechanism comprising an oscillatory member, a projecting member on the number wheel to actuate said oscillatory member at each complete revolution of the wheel, a rocker member on the driving arm adapted to contact with the pawl-carrying-arm, a holding member to hold the rocker against movement relative to the driving-arm, and a trip arm on the oscillatory member adapt-

ed to release said holding means to permit the rocker to give the pawl-carrying arm an extra movement and means to impel said rocker member in said movement.

8. In a calculating machine, in combination with a series of number wheels, a main shaft, a wheel turning gear, a gear operating mechanism, an oscillatory member, a shaft therefor, said oscillatory member having a momentum stop-lug for the gear operating mechanism, means to give the gear mechanism an extra movement after its actuation by the main shaft, holding means to hold said last means inoperative, a trip on said oscillatory member, and means carried by the number wheels to rock said oscillatory member to remove the stop from the path of the gear operating mechanism and to throw said trip into line with the holding means whereby the latter is released.

9. In a calculating machine, in combination with a series of number wheels and a main operating shaft, a number wheel actuating mechanism, means to give said mechanism an extra movement to carry over the calculation from one wheel to a wheel of the next higher series, holding means for said carrying means, a controlling member for said carrying means, comprising a member oscillatory on a shaft, said member having a stop to limit the movement of the wheel actuating mechanism, and having a trip to release the holding means, means whereby said controlling member is rocked by a number wheel on the complete revolution of the latter to remove said stop and to operatively position said trip and means to restore said controlling member to normal position.

10. In a calculating machine, in combination with a series of number wheels and a main operating shaft, a number wheel actuating mechanism, means to give said mechanism an extra movement to carry over the calculation from one wheel to a wheel of the next higher series, holding means for said carrying means, a controlling member for said carrying means, comprising a member oscillatory on a shaft, said member having a stop to limit the movement of the wheel actuating mechanism, and having a trip to release the holding means, means whereby said controlling member is rocked by a number wheel on the complete revolution of the latter to remove said stop and to operatively position said trip, a latch to hold said controlling member in carrying position and means to release the latch and permit the return of said member to normal position.

11. In a calculating machine, in combination with a series of number wheels and a main shaft, a number wheel driving gear, a pawl therefor, a pawl-carrying arm, means to actuate said arm an oscillatory member, means to rock said member by the number

wheel, said member having a momentum stop for the pawl-carrying arm, said stop being separated from the end of the pawl-carrying arm when the latter is in its normal actuating position, said stop being moved out of the path of the arm when the member is rocked by the number wheel.

12. In a calculating machine, in combination with a series of number wheels and a main shaft, a driving arm actuated by the main shaft, a number wheel driving gear, a pawl for said gear, a pawl-carrying arm, a bell crank member, a shaft on which said member is mounted, said bell crank having a tooth, a lip on each wheel to engage said tooth, a stop on said member to limit the momentum movement of the pawl-carrying arm of the next higher wheel, a trip on said bell crank, a rocker to give said pawl-carrying arm of the higher wheel a movement independent of that imparted by the driving arm, a trigger to hold said rocker inoperative and adapted to be released therefrom by said trip to permit the rocker to actuate the pawl-carrying arm and means to impel said rocker.

13. In a calculating machine, in combination with a series of number wheels and a main operating shaft, a series of bell crank members, means on each wheel for rocking a bell crank member, a wheel actuating means for each wheel, a momentum stop on said member for the actuating means of the adjoining wheel, a driving-arm actuated from the main shaft for driving said wheel actuating means, and a lock carried by said driving-arm and movable therewith into position to lock the wheel actuating means at the beginning of the movement thereof to prevent displacement of the actuating means by the stop or otherwise.

14. In a calculating machine, in combination with a series of number wheels and a main operating shaft, a gear for each wheel, a pawl for said gear, a pawl-carrying arm for each pawl, a bell crank member having a stop for the pawl-carrying arm, a driving arm for the pawl-carrying arm operated from the main shaft, a pawl-lock member carried by the driving-arm and movable into locking position at the initial movement of the driving-arm.

15. In a calculating machine, in combination with a series of number wheels and a main operating shaft, a gear for each wheel, a pawl and pawl-carrying arm for each gear, keys for setting said pawl-carrying arms at predetermined operating positions, driving arms actuated by the main shaft, said arms having parts to contact with the pawl-carrying arms, and having lugs extending over the pawls and forming pawl-locks, and a stop member movable into and out of the path of the pawl-carrying arm.

6. In a calculating machine, a number

wheel, a series of keys, a gear and pawl for actuating each wheel, throughout the entire movement required to register the number of a selected key, an operating handle for said gear and pawl a stop member for arresting the movement of each pawl at the end of each movement, and movable in the same plane with that of the movement of the pawl and means for moving the stop member to allow the pawl to make an extra movement, and means additional to the operating handle for imparting said extra movement to the pawl and gear.

17. In a calculating machine, a number wheel, a gear, a pawl, a pawl carrying-arm, a handle for operating said arm, a bell crank in line with and movable in the same plane with the pawl-carrying arm, means to move the bell crank to present different parts thereof as stops to limit the movements of the pawl-carrying arm, means for actuating the pawl-carrying arm and means additional to the operating handle for giving the same an extra movement at the end of its normal stroke.

18. In a calculating machine, a number wheel, actuating means therefor, a bell crank stop-member co-acting with the actuating means, means carried by the adjoining wheel of the lower column to rock said bell crank to move a part thereof out of the path of the actuating means to permit an extra movement thereof, a spring-pressed latch movable into engagement with the bell crank before the actuation of the number wheel and releasable from such engagement after such actuation.

19. In a calculating machine, in combination with a series of number wheels, a main operating shaft, means actuating each wheel throughout the entire movement required to register the number of a selected key, an oscillatory stop member for arresting the actuating means at the end of each movement, means carried by an adjoining wheel for moving the member to a position to allow the actuating means to make an extra movement, a latch for each stop member for holding the same in said position during the registering movement, a spring for pressing said latch into such engagement, a bail common to all the latches for moving them out of engagement with the stop member and an operative connection between the bail and the main shaft.

20. In a calculating machine, a series of number wheels, a main operating shaft, wheel actuating means, a stop member for said actuating means, a latch to engage said stop-member, a bail to release said latch, and a cam-plate on the main shaft to rock said bail.

21. In a calculating machine, in combination with a series of number wheels, a gear for each wheel, actuating means for each

gear, a member movable by the number wheel to present different stops to the actuating means, a latch to hold the stop member in one position, a spring pressing against said latch, a detent for holding the gear against forward movement, a spring for pressing said detent, operating means for releasing said latch and for releasing said detent, connecting means between the two sets of operating means whereby the tension of one spring is exerted against that of the other and means whereby the operating shaft operates said connecting means.

22. In a calculating machine, in combination with a series of number wheels and a main operating shaft, a gear for each wheel, actuating means for said gear, a stop-member for the actuating means, a latch to hold said member in one position, a forward movement retaining detent for said gear, a spring for said latch and a spring for said detent, a bail for releasing the latch and a bail for releasing the detent, a link connecting said bails and a common cam for actuating said bails, said cam operated by the main shaft.

23. In a calculating machine, a number wheel, a gear wheel for turning the same, a detent for locking the gear normally against forward movement, gear actuating means, keys for setting the actuating means, a movable member having stops for the actuating means, a latch for said stop member to hold the same in position to permit an extra movement of the actuating means, a lock for said actuating means, whereby said operating lever in its working stroke first frees the forward locking detent and operates the actuating means lock, and then operates the wheel actuating means, and means whereby the lever frees the latch before the beginning of its next working stroke.

24. In a calculating machine, a main operating shaft, a series of number wheels, a slideable and rotatable shaft on which said wheels are mounted, means to normally hold the shaft against both endwise and rotatable movement, a series of interrupted grooves in said shaft, pawls on said wheels to engage said grooves when the shaft is shifted longitudinally, and means to rotate said wheel shaft from the main shaft when the shaft and wheels are fixed together.

25. In a calculating machine, a main shaft, a series of number wheels, a shaft on which said wheels are mounted, an interrupted series of grooves in the shaft extending longitudinally thereof, spring pressed pawls carried by the wheels and adapted to project into said grooves, said wheel shaft capable of rotatable and longitudinally slideable movement, means to hold it against said movements, a pinion on said shaft and a gear on the main shaft adapted to mesh with said pinion on the longitudinal adjustment

of the shaft, said wheels having means to lock said wheels in said grooves against rotation on the shaft.

26. In a calculating machine, a series of number wheels, a shaft on which said wheels are mounted, means to permit the rotation of said wheels on the shaft and means to lock the wheels close together, said shaft having a pin and hole connection to prevent rotation thereof and slidable longitudinally to release said pin.

27. In a calculating machine, in combination with a series of number wheels, a main operating shaft, a series of keys, said keys having projections thereon, a series of sliding repeating bars having projections adapted to ride over the projections of the keys and a bail and handle for operating said bars.

28. In a calculating machine, in combination with a series of number wheels, a series of keys, wheel setting means controlled by the keys, a lever adapted to engage and operate said setting means when set and before the actuation thereof and a key for operating said lever.

29. In a calculating machine, in combination with a series of number wheels, a series of keys, wheel setting means controlled by the keys and actuated thereby on the depression of a key, a detent for locking the means normally, a lever for releasing the setting means from set position and returning it to engagement with the detent and the key to normal position, and a key for operating said lever.

30. In a calculating machine, in combination with a series of number wheels, a series of keys, a releasable slide bar for each key, a wheel actuating means connected to said slide bar and set in actuating position thereby, a swinging member adapted to contact with the actuating means to restore the same and the slide bar to normal position and means to operate said swinging member.

31. In a calculating machine, in combination with a series of number wheels, a series of keys, a slide bar for each series of keys, a spring for said slide bar, means whereby the depression of a key permits the spring to move the slide bar, said bar having a stop to engage the key when so moved, a pawl connected intermediately to the slide bar, a gear actuated by said pawl and actuating a number wheel, a lever adapted to remove said pawl from engagement with the gear to return the slide bar and permit the key to rise, and means to operate the lever.

32. In a calculating machine, a main operating shaft, type, a platen, a link for swinging said platen, a cam on the main shaft for actuating said link, a key and means carried by the main shaft for bringing said lever against the link after the im-

pression actuation thereof to give a quick return to the link and platen.

33. In combination, with a type wheel, a tilting platen carrying carriage, a detent for the type wheel and means carried by the carriage to force said detent into engagement with the type wheel.

34. In combination with a series of type wheels, a tilting platen carrying carriage, a detent bail extending across the type wheels and a projecting member carried by the carriage and adapted to force the detent bail into engagement with the type wheels.

35. In a machine of the class described, in combination with a series of number wheels and their respective actuating means, a series of type wheels, a link connected to each number wheel actuating means, a gear for setting each type wheel, said gear wheels having bars set at successive varying distances from front to rear respectively and means to connect such bars to the links.

36. In a machine of the class described, in combination with a number wheel, a wheel actuating means, a link lying throughout its length in the same vertical plane and connected to the actuating means whereby the link will exert a straight pull, a pivoted arm connected to said link, a bar connected to said arm and at right angles thereto, a type wheel, a type wheel turning gear, said bar carried by an arc-shaped arm of said gear, the succeeding arc-arms of a series of said gears being arranged in advance of one another at different distances from the gear axis, whereby the bars are free to pass one another upon the turning of the gears.

37. In a calculating machine, a number wheel, mechanism for carrying numerals from a lower column to a higher column, and controlled by the number wheel, said number wheel carrying a rocker for actuating the carrying mechanism and means for actuating the rocker.

38. In a calculating machine, a number wheel, mechanism for carrying numerals from one column to a higher column, and means for positively actuating the carrying mechanism including an actuating member associated with the number-wheel, said carrying mechanism actuating member being inoperative up to the "9" position and being positioned by the movement of the wheel to operate between the "9" and "10" position.

39. In a calculating machine, a number wheel, mechanism for carrying numerals from a column to a higher column, and controlled by the number wheel, a rocker carried by the number wheel for actuating the carrying mechanism, a spring pressing said rocker in one direction and holding it normally inoperative, and means for positioning said rocker in operative position and for releasing it to permit it to actuate the carrying mechanism.

40. In a calculating machine, a number wheel, mechanism for carrying from a column to a higher column, a pivoted rocker carried by the number wheel, a trip carried by the carrying mechanism, means to bear against one end of the rocker to tilt the rocker into the path of the trip and means to carry the rocker against the trip to actuate the latter.
41. A calculating machine comprising the combination of a plurality of wheels rotatable about an axis, a pawl for each wheel rotatable concentric therewith, a row of keys for each wheel, a slide-bar coacting with each row of keys and movable lengthwise when a key is depressed, a connection from each slide-bar to the corresponding pawl, an operating device movable in a forward direction to carry it into coöperative relation to the pawls and then to actuate the pawls and return the slide-bars to their initial positions and movable in the opposite direction to return to initial position, a plurality of printing-members, a connection from each slide-bar to a corresponding printing-member, a platen coacting with the printing-members, and means for actuating the platen to effect the printing during the forward movement of the operating device but before the slide-bars are actuated to return them to initial position, substantially as set forth. 70
42. A calculating-machine comprising the combination of a plurality of wheels rotatable about an axis, a pawl for each wheel rotatable concentric therewith, a row of keys for each wheel, a slide-bar coacting with each row of keys and movable lengthwise when a key is depressed, a connection from each slide-bar to the corresponding pawl, carrying mechanisms each controlled by the operation of a wheel and adapted to operate the wheel of next higher order, an operating device movable in a forward direction to carry it into coöperative relation to the pawls and then to actuate the pawls and return the slide-bars to their initial positions and movable in the opposite direction to return to initial position and reset an element of each carrying mechanism, a plurality of printing-members, a connection from each slide-bar to a corresponding printing-member, a platen coacting with the printing-members, and means for actuating the platen to effect the printing during the forward movement of the operating device but before the slide-bars are actuated to return them to initial position, substantially as set forth. 75
43. A calculating-machine comprising the combination of a plurality of wheels rotatable about an axis, a pawl for each wheel rotatable concentric therewith, a row of keys for each wheel, a slide-bar coacting with each row of keys and movable lengthwise when a key is depressed, a connection from each slide-bar to the corresponding pawl, an operating device movable in a forward direction to carry it into coöperative relation to the pawls and then to actuate the pawls and return the slide-bars to their initial positions and movable in the opposite direction to return to initial position, a plurality of number-wheels each geared to one of said wheels, a shaft on which the number-wheels 80
- were when a key is depressed, a connection from each slide-bar to the corresponding pawl, an operating device movable in a forward direction to carry it into coöperative relation to the pawls and then to actuate the pawls and return the slide-bars to their initial positions and movable in the opposite direction to return to initial position, means movable with the operating device for holding the pawls in engagement with their respective wheels while the operating device is actuating the pawls, a plurality of printing-members, a connection from each slide-bar to a corresponding printing-member, a platen coacting with the printing-members, and means for actuating the platen to effect the printing during the forward movement of the operating device but before the slide-bars are actuated to return them to initial position, substantially as set forth. 85
44. A calculating-machine comprising the combination of a plurality of wheels rotatable about an axis, a pawl for each wheel rotatable concentric therewith, a row of keys for each wheel, a slide-bar coacting with each row of keys and movable lengthwise when a key is depressed, a connection from each slide-bar to the corresponding pawl, carrying mechanisms each controlled by the operation of a wheel and adapted to operate the wheel of next higher order, said mechanisms being arranged to prevent excessive movement of a wheel under the actuation of a carrying mechanism, an operating device movable in a forward direction to carry it 90
- into coöperative relation to the pawls and then to actuate the pawls and return the slide-bars to their initial positions and movable in the opposite direction to return to initial position and reset an element of each carrying mechanism, a plurality of printing-members, a connection from each slide-bar to a corresponding printing-member, a platen coacting with the printing-members, and means for actuating the platen to effect the printing during the forward movement of the operating device but before the slide-bars are actuated to return them to initial position, substantially as set forth. 95
45. A calculating-machine comprising the combination of a plurality of wheels rotatable about an axis, a pawl for each wheel rotatable concentric therewith, a row of keys for each wheel, a slide-bar coacting with each row of keys and movable lengthwise when a key is depressed, a connection from each slide-bar to the corresponding pawl, an operating device movable in a forward direction to carry it into coöperative relation to the pawls and then to actuate the pawls and return the slide-bars to their initial positions and movable in the opposite direction to return to initial position, a plurality of number-wheels each geared to one of said wheels, a shaft on which the number-wheels 100
- 105
- 110
- 115
- 120
- 125
- 130

are normally loosely mounted, means for re-setting the number-wheels at zero, a plurality of printing-members, a connection from each slide-bar to a corresponding printing-member, a platen coacting with the printing-members, and means for actuating the platen to effect the printing during the forward movement of the operating device but before the slide-bars are actuated to return them to initial position, substantially as set forth.

46. A calculating-machine comprising the combination of a plurality of wheels rotatable about an axis, a pawl for each wheel rotatable concentric therewith, a row of keys for each wheel, a slide-bar coacting with each row of keys movable lengthwise when a key is depressed, a connection from each slide-bar to the corresponding pawl, carrying mechanisms each controlled by the operation of a wheel and adapted to operate the wheel of next higher order, said mechanisms being arranged to prevent excessive movement of a wheel under the actuation of a carrying mechanism, an operating device movable in a forward direction to carry it

into coöperative relation to the pawls and then to actuate the pawls and return the slide-bars to their initial positions and movable in the opposite direction to return to initial position and reset an element of each carrying mechanism, means movable with the operating device for holding the pawls in engagement with their respective wheels while the operating device is actuating the pawls, a plurality of printing-members, a connection from each slide-bar to a corresponding printing-member, a platen coacting with the printing-members, and means for actuating the platen to effect the printing during the forward movement of the operating device but before the slide-bars are actuated to return them to initial position, substantially as set forth.

In testimony whereof I affix my signature, in presence of two witnesses.

WILLIAM P. QUENTELL.
